UNITED STATES PATENT OFFICE

JOHN EDWARD THORNTON, OF WEST HAMPSTEAD, LONDON, ENGLAND, ASSIGNOR TO
JOHN OWDEN O'BRIEN, OF MANCHESTER, ENGLAND

MULTICOLOR SCREEN FILM

Application filed February 16, 1927, Serial No. 188,765, and in Great Britain March 16, 1926.

This invention relates to the manufacture of multi-color screens and film-supports for the production of negatives or positives of the multi-color screen-type, and is applicable to thin flexible films for roll-film, camera-cartridges and film-packs, also for thick stiff flat films, rigid glass plates, and for continuous kinematograph film.

The object of the invention is to form the color screen in two parts or two half-screens by purely photographic and dye processes, obviating the need for any printing and subsequent washing away of fatty-resists or other equivalent methods generally used in screen making, and then to combine such half-screens by crossing the lines of one upon the other to produce the required mosaic pattern, and in forming such half-screens upon opposite sides of a central transparent support or upon two thin supports that are eventually cemented together to make up such support.

It has already been proposed in the production of two color screens to print resist lines in printing ink, fatty or resinous substances, dye the celluloid spaces, between, remove the resist, and dye the clear spaces left. Many modifications of this system have been proposed, and in practically all these methods the several colors have been applied to one side of the support, and it has been necessary to accurately register one color with the other to produce a suitable mosaic. The necessity for such accurate registration has made all these methods of little or no value for manufacture upon a large scale.

The fact that the present system dispenses with registration entirely obviates this great objection; and the fact that the screen is made in two parts as two half-screens still further simplifies the manufacturing processes; and the use of purely photographic printing methods reduces such manufacture to processes of great precision, simplicity, regularity of results, and enables the product to be turned out entirely by automatic machinery.

The invention consists of a single and complete multi-color screen and support comprising four or three colors manufactured

without need for any registration by crossing two half screens which are respectively formed upon opposite sides of a transparent support or upon two transparent supports, one half screen being produced with two colors by alternating lines of insoluble colored and non-insoluble colored colloid and the other half screen being produced with two different colors by alternating lines of insoluble colored and non-insoluble colored colloid or with lines of one color alternating with transparent non-colored lines, the colors being eventually mordanted and fixed, the correct colorings being obtained by crossing the colors on the two half-screens.

The invention will be described with reference to the accompanying drawings:—

Figs. 1 and 2 show two arrangements of four-color screens built up from two half-screens.

Figs. 3 and 4 show two arrangements of three-color screens built up from two half-screens.

Fig. 5 shows another arrangement of four-color screen built up from two half screens in which the lines ran diagonally on each screen.

Fig. 6 is another arrangement of four-color screen built up from two half screens in which the lines on one screen are diagonal and on the other screen are longitudinal or transverse.

Fig. 7 is a perspective view of a strip of kinematograph film-support formed in accordance with the invention.

Fig. 8 is a section of same.

Fig. 9 is a section of a camera film with a non-curling gelatine layer on the back thereof.

Fig. 10 is a section of a relatively thick support of non-flexible or non-rollable type such as glass plates or very thick celluloid.

Fig. 11 is a perspective view of a strip of kinematograph film support formed in accordance with the invention in which the two films are united back to back and

Fig. 12 is a perspective view of a strip of kinematograph film support formed in accordance with the invention in which the two half screens are united back to face.

In carrying out the invention as applied

to two thin films which are ultimately cemented together to form a single support as in specification of Patent No. 1,670,671 dated May 22, 1928 one face of each thin film is coated with a sensitized colloid, which is then printed by exposure through a line-screen, until the portions of colloid exposed through the clear spaces are rendered insoluble and non-absorbent; the portions protected by the opaque lines of the screen remain soluble and absorbent.

The four-color screen shown in Fig. 1 is built up from the two half-screens, one of which contains the complementary pair of colors red and blue-green, and the other contains the complementary pair of colors, yellow and violet, the colors in each pair being exactly complementary to each other; producing when the two half screens are superimposed and cemented together, in a crossed position, a support and screen comprising the following colors:—orange, blue-violet, green and red-violet.

The four-color screen shown in Fig. 2 is built up from two half-screens, one of which contains the complementary pair of colors, red and green, crossed by the complementary pair of colors, blue and yellow in the other half-screens producing a finished support and screen comprising the following colors:—Violet, orange, yellow-green and blue-green.

One arrangement of a three-color screen, built up from the half-screens is shown in Fig. 3, one half-screen contains red and yellow close together, and crossed by the other containing the single color blue separated by uncolored spaces; producing when the two half-screens are superimposed and cemented together with the blue crossing the red and yellow a support and screen comprising the following colors:—Red, yellow, violet and green.

A similar arrangement of a three-color screen built up from two half-screens is shown in Fig. 4, one half-screen contains red and yellow-green, crossed by the other containing the single color blue separated by uncolored spaces; producing a finished support and screen comprising the following colors:—Red, yellow-green, violet and blue-green.

In the three-color groups Figs. 3 and 4 the pair of colors are not exactly complementary, as is the case in the four-color groups.

In the arrangement shown in Fig. 5 the screen is built up from two two-color half screens, one half screen containing the colors red and blue and the other the colors yellow and violet as in Fig. 1 but the lines of color on each half screen are arranged diagonally.

In the arrangement shown in Fig. 6 the screen is built up from two two-color half screens, one half screen containing the colors red and blue and the other the colors yellow and violet as in Fig. 1, but the lines of color

of one screen are arranged diagonally and on the other either vertically or transversely.

Figs. 7 and 8 show a kinematograph film produced according to the invention, being built up of two thin celluloid layers forming the support each bearing a half-screen layer, the two thin films, which are each half-supports, being cemented together with the screens inside. There is thus formed a single support of the flexible-film type, upon one side of which is then coated first an adhesive substratum and then a sensitive layer of panchromatic gelatino-silver-bromide emulsion.

There is thus produced a flexible or rollable film of any size or width such as employed for roll-film cameras, for film-packs, or for kinematograph film-ribbons.

Fig. 9 shows a similar film one face of which is coated with an adhesive substratum and then a sensitive layer of panchromatic gelatino-silver-bromide emulsion, and the other face with a layer of gelatine on the back of the same thickness as the layer of emulsion on the other face, thus forming a non-curling film suitable for roll-film cameras and film packs for such as a non-roll camera film.

In Fig. 10 the invention is illustrated as applied to thicker supports of the non-flexible or non-rollable description, such as glass plates or very thick stiff celluloid films. One half the screen is formed upon such thick support, the other half being formed upon an extremely thin support of celluloid (as in Figs. 7 and 8) which is cemented to the stiff half of the support, with the screens inward. The face of the celluloid is next coated with an adhesive substratum and finally with a panchromatic emulsion as described with reference to Figs. 7 and 8.

Instead of the two half screens being united together face to face as shown in Figs. 7 and 8 they may be united back to back as shown in Fig. 11 or back to face as shown in Fig. 12.

The approximate thickness of the various layers of the film illustrated in Figs. 7 to 12 are as follows:—For the films—

Each celluloid layer $\frac{1}{1000}$ inch thick.

Each screen layer $\frac{1}{5000}$ inch thick.

Each cement layer $\frac{1}{10000}$ inch thick, these three layers duplicated forming a complete flexible support.

One substratum layer $\frac{1}{1000}$ inch thick.

One emulsion layer $\frac{1}{100}$ inch thick these latter being applied to one of the outer faces of the flexible support.

Where a non-curling film is required the other face is provided with:—

A substratum layer $\frac{1}{1000}$ inch thick.

A gelatine layer $\frac{1}{5000}$ inch thick.

For thick rigid films the celluloid is $\frac{1}{100}$ inch thick and for glass plates the glass is about $\frac{3}{2}$ inch thick, the other layers remaining the same.

All the above figures are approximate and may be varied as required.

In all cases the colloid comprises a very thin layer of gelatine, fish-glue, albumen, or the like or a mixture thereof. The sensitizer preferably is a solution of a bichromate salt. The coloring matter is a suitable dye comprising one color of the complete set of colors. The dye and sensitizer may be mixed with the colloid before it is applied to the support by the usual coating apparatus. Or one only may be incorporated with the colloid, the other being applied after the coating has been dried by passing the coated support through a bath until sufficient of either the dye or sensitizer as the case may be has been absorbed.

After the colloid layer has been exposed and printed as aforesaid it is well washed to remove all dye and sensitizer from the parts that were covered by the opaque lines of the screen, and which still remain soluble, so that there is no difficulty in removing the sensitizer and color. The other lines corresponding to the transparent lines of the screen have become insoluble and the dye is therefore locked up therein, the result being a colloid layer comprising insoluble colored lines with absorbent uncolored spaces between.

The layer is then dried in order to thoroughly harden the insoluble lines, after which the intermediate absorbent lines of colloid are dyed with another color. This exactly fills the spaces between the insoluble colored lines, the final result after slight rinsing in water and subsequent drying being to produce a line-screen of two colors. The second colored lines are finally mordanted or rendered insoluble to prevent the color washing out.

In the case of a color screen-support containing three colors as shown in Figs. 3 and 4 the second thin film is printed by similar methods but with the difference that only one set of lines are printed and colored, the intermediate spaces being left uncolored.

In the case of a color screen-support containing four colors as shown in Figs. 1 and 2 two colors are formed on the second thin-film by dyeing the intermediate lines as first described.

Instead of sensitizing the screen-layers with a bichromate salt, iron or other suitable salts may be used. Or silver sensitizing may be substituted, in which case the exposed layer requires developing and afterwards treating with an oxidizing bath that will render the colloid insoluble in direct ratio to the deposit of metallic silver. This brings the colloid to practically the same insoluble and soluble conditions as in the hereinbefore described bichromate method. The final step is to dissolve the silver by any suitable known bath in order to leave transparent (in-

stead of opaque) colored lines and then to thoroughly wash the film.

What I claim as my invention and desire to protect as my invention is:—

1. A multi-color screen and support comprising a transparent support a plurality of lines in insoluble colored colloid printed upon one side of said support, a plurality of differently colored dyed lines alternating with the printed lines on said support, a second transparent support, a plurality of lines in insoluble colored colloid printed upon one side of the second support, a plurality of differently colored dyed lines alternating with the printed lines in the second supports, the printed and dyed lines on the second support being differently colored from those on the first support, the two supports being assembled with the printed lines on one crossing the printed lines on the other to form the complete color screen.

2. A process for the manufacture of a multi-color screen upon two transparent supports which consists in coating each support with differently colored colloid photographically printing a plurality of insoluble lines upon the colloid washing away the unprinted soluble colloid, dyeing the spaces between the printed lines in different colors differing from the printed lines and assembling the two half screens with the lines on one crossing the lines on the other.

3. A multi-color screen and support formed from two photographically produced multicolor pattern half-screens crossed to avoid registration, an adhesive substratum coated upon one side of the support and a layer of sensitive panchromatic gelatino-silver-halid emulsion superimposed upon the substratum.

4. A multi-color screen and support formed from two photographically produced multi-color pattern half-screens crossed to avoid registration, an adhesive substratum coated upon one side of the support, a layer of sensitive panchromatic gelatino-silver-halid emulsion superimposed upon the substratum, a second adhesive substratum coated upon the other side of the support and a layer of non-sensitive plain gelatine upon the second substratum.

In testimony whereof I have hereunto set my hand.

JOHN EDWARD THORNTON.
